US00D876440S

(12) **United States Design Patent** (10) **Patent No.:** **US D876,440 S**
(45) **Date of Patent:** **** Feb. 25, 2020**

(54) **POWER ADAPTOR**

(71) Applicant: **A9.COM. INC.**, Seattle, WA (US)

(72) Inventors: **Paul Nangeroni**, San Francisco, CA (US); **Paul Kelley**, San Francisco, CA (US); **Nicholas Reid**, San Francisco, CA (US); **Nathaniel C. Hardison**, San Francisco, CA (US); **Nicholas S. Weaver**, San Francisco, CA (US); **Timothy Amos Schallich**, San Francisco, CA (US)

(73) Assignee: **A9.COM. Inc.**, Seattle, WA (US)

(**) Term: **15 Years**

(21) Appl. No.: **29/667,936**

(22) Filed: **Oct. 25, 2018**

Related U.S. Application Data

(63) Continuation of application No. 29/583,574, filed on Nov. 7, 2016, now Pat. No. Des. 836,114.

(51) **LOC (12) Cl.** **14-02**

(52) **U.S. Cl.**

USPC **D14/433**

(58) **Field of Classification Search**

USPC D13/108; D14/433, 435.1, 432, 358
CPC H01M 10/44

See application file for complete search history.

(57) **CLAIM**

We claim the ornamental design for a power adaptor, as shown and described.

DESCRIPTION

FIG. 1 is an isometric view, from the front right, of the top of the power adaptor;

FIG. 2 is a plan view of the top of the power adaptor;

FIG. 3 is an elevation view of the front of the power adaptor;

FIG. 4 is an elevation view of the right of the power adaptor;

FIG. 5 is an elevation view of the back of the power adaptor;

FIG. 6 is an elevation view of the left of the power adaptor;

FIG. 7 is a plan view of the bottom of the power adaptor; and,

FIG. 8 is an isometric view, from the bottom left, of the back of the power adaptor.

1 Claim, 2 Drawing Sheets
